UNITED STATES PATENT OFFICE.

WILLIAM F. BAKER, OF ANTLERS, OKLAHOMA.

ENGINE FOR GRATE-SHAKERS.

975,314.

Specification of Letters Patent.

Patented Nov. 8, 1910.

Application filed July 24, 1909. Serial No. 509,426.

To all whom it may concern:

Be it known that I, WILLIAM F. BAKER, a citizen of the United States, residing at Antlers, in the county of Pushmataha and State of Oklahoma, have invented new and useful Improvements in Engines for Grate-Shakers, of which the following is a specification.

This invention relates to engines for grate shakers and the object of my invention resides principally in the provision of a steam cylinder wherein is mounted for reciprocatory motion a piston adapted to be operatively connected with a grate, preferably of the rocking type.

A still further object of my invention resides in the provision of a three way valve and the provision of a two way valve, the former being adapted for operation to alternately admit steam to the ends of the cylinder so as to impart the desired reciprocatory motion to the piston, and the latter being employed for the purpose of establishing an equal pressure of steam at both sides of the piston head.

Other objects and advantages will be apparent as the nature of the invention is better disclosed, and it will of course be understood that changes within the specific scope of the claim can be made without departing from the spirit of the invention.

In the drawings forming a portion of this specification and in which like numerals of reference indicate similar parts in the several views, Figure 1 is a longitudinal section through the steam cylinder piston of my improved mechanical grate shaker. Fig. 2 is a transverse section taken on the line 2-2 of Fig. 1. Fig. 3 is a detail section 40 through the inlet valve. Fig. 4 is a similar view through the valve for the by-pass.

My improved engine consists principally of a steam cylinder 1 which is disposed horizontally and is provided with removable heads 2 and 3. The head 3 is formed with a centrally located gland or packing box 4 through which the piston rod 5 is adapted to reciprocate. The piston rod 5 is provided with a hollow piston 6 which has formed 50 therein upon its peripheral face a pair of spaced annular grooves for the reception of packing rings 7. The inner faces of the heads 2 and 3 are provided with suitable well known cushioning elements 8 such as rubber or the like. A steam pipe is indicated at 9 and may be connected in any well

known manner with a main source of steam supply. This pipe carries a three way rocking valve 10 to which is connected oppositely directed conveying pipes 11 and 12 the former being tapped into the head 2 and the latter tapped into the head 3. The three way valve as will be understood can be of any well known form and any suitable well known means may be employed for imparting the desired rocking movement to the valve so that steam from the main source of steam supply can be alternately admitted to the ends of the cylinder.

From the construction just described it will be seen that when rocking motion is imparted to the valve 10 the steam as stated will be alternately admitted to two ends of the cylinder whereby reciprocatory motion will be imparted to the piston 6.

The cylinder 1 is provided approximately at its center with suitably spaced exhaust ports 13 and 14 which are adapted to be alternately covered and uncovered to permit the discharge of dead steam.

When the apparatus is in its normal or non-working stage it is desirable to hold the piston at the center of the cylinder and to accomplish this end I provide a two way rocking valve 15 which is connected with oppositely extending by-pass pipes 16. These pipes are tapped into the walls of the cylinder 1 and are disposed at the sides of the center of the cylinder. In operation of the herein described engine steam is conveyed alternately to the pipes 11 and 12 so as to reciprocate the piston as before mentioned. When the grate has been operated to the desired extent and it is desirable to have the motion of the piston cease, the valve 10 is shut off manually immediately after the passing of the piston beyond one of the exhaust ports and the valve 15 opened. In this manner the steam from one end of the cylinder can be partly conveyed to the other end whereby an equal distribution of the steam's energy will be distributed to two sides of the piston, thus holding the piston centrally of the steam cylinder and in a position to close both steam exhaust ports 13 and 14.

Claim:

In an engine for grate shakers, a cylinder having its heads provided with cushioning elements, a fluid conveying pipe opening at its ends directly into the ends of the cylinder, a rock valve located in the said pipe, the

said cylinder having spaced exhaust ports formed therein midway between its ends, a piston mounted for reciprocatory motion in the cylinder, a pipe having its ends extended 5 into the cylinder at points adjacent to the said exhaust ports thereof and designed to distribute the working fluid to opposite ends of the cylinder to cause the piston to be positioned immediately between the ends of the 10 cylinder in position to close the exhaust

ports when the valve of the fluid inlet is closed, and a controlling valve located in the second named pipe.

In testimony whereof I affix my signature in presence of two witnesses.

WILLIAM F. BAKER.
